UNITED STATES PATENT OFFICE.

GLENN L. MARTIN, OF LOS ANGELES, CALIFORNIA, ASSIGNOR TO GLENN L. MARTIN COMPANY, OF LOS ANGELES, CALIFORNIA, A CORPORATION OF CALIFORNIA.

PACKED PARACHUTE.

1,165,891.

Specification of Letters Patent. Patented Dec. 28, 1915.

Application filed March 10, 1914. Serial No. 823,664.

To all whom it may concern:

Be it known that I, GLENN L. MARTIN, a citizen of the United States, residing at Los Angeles, in the county of Los Angeles and 5 State of California, have invented new and useful Improvements in Packed Parachutes, of which the following is a specification.

This invention relates to packed parachutes, and it has for its object to provide 10 efficient and reliable safety-alighting means, operating on the principle of the parachute, whereby aeronauts and aviators may safely descend to earth through the air, together with devices, adjuncts, and features associated with such parachute device and adapted 15 to be carried, worn and stored in compact form, and to be attached to and operated in connection with flying machines, balloons, airships and other apparatus and vessels for 20 navigating and traversing the air.

In using parachutes of the usual construction, and in the usual manner, many objections arise incident to the storage, operative extension for use, manipulation and utilization 25 of the same, which render the same under many circumstances wholly unreliable, particularly in emergencies, and also for purposes of unfailing service in exhibition and demonstration.

It is a particular object of the present invention to provide a packed parachute device which may be worn by aviators and others, and attached to aerial craft, or simply attached to the user and to the craft, and 35 which, reduced to a compact form, will, at all times, be available for use, and which may be put into service by the simple act of subjecting the same or certain features of the same to a strain such as that imparted 40 by the aviator or other user upon his voluntary or involuntary act, as when cast from, or casting himself from, an aerial vessel. In accordance with the invention, this act of the user inaugurates a sequence of operations 45 affecting the packed parachute which unpack or liberate the parts and features of the parachute successively, obviating any risk of entangling or fouling the various parts and features of the parachute or involving 50 the same in entanglement with or interference by the user and the aerial vessel with which the device co-operates in action. The final liberating action cuts away the otherwise fully freed parachute from the flying machine or other apparatus or vessel, 55

and the weight of the user, who is suspended from the parachute, almost immediately, upon slight further descent, causes the parachute to be finally extended in condition for use and service. The package or container 60 *per se* is left attached to the flying machine or the like, and can in no way interfere with the liberated and operative parachute. The user thus descends safely.

The invention has for its object to provide 65 a packed parachute device of the general nature stated which will be superior in point of relative simplicity and inexpensiveness of construction and organization, taken in connection with positiveness in operation, compactness in form, lightness in weight, uniform reliability and simplicity in action, and which will be generally superior in efficiency and serviceability.

With the above and other objects and 70 leading features entering into the construction and combination and organization of the same and the parts of the same, the invention consists in the novel and useful provision, formation, construction, association 75 and relative arrangement of parts, members and features, all as hereinafter described, shown in the drawings, and finally pointed out in claims.

In the drawings: Figure 1 is a side elevation of a packed parachute with the parts and features in packed form and connected with a jacket, vest or other garment or device which is applied to the person of the user; Fig. 2 is a longitudinal vertical sectional view of the same, upon an enlarged scale, the whole being applied to a structural member of an aeroplane or the like; Fig. 3 is a view in elevation of the parachute device and user's vest in the relative positions assumed after the second stage of drop or descent of the user; Fig. 4 is a similar view showing the general position and condition of the several parts and features during the third stage of drop or descent of the user; Fig. 5 is a similar view making a similar showing during the fourth stage of drop or descent of the user; Fig. 6 is a similar view illustrating similarly during the fifth stage of drop or descent of the user; and Fig. 7 is 85 a view similar to Fig. 1, illustrating the substitution of a further parachute device for the means of connection shown in the other figures between the packed parachute and the aeroplane or other construction. 90 95 100 105 110

Corresponding parts in all the figures are designated by the same reference characters.

Referring with particularity to the drawings, the packed parachute, as a complete device or apparatus, is shown as comprising three main or essential elements or groups of elements, namely a container or holder A, the parachute device *per se* B which is normally housed or packed within the container, and securing means C whereby the container and the features normally stored therein may be connected with the body of the user and, if desired, carried by the user as a pack.

D in the drawing designates a frame or structural member of a flying machine, balloon or the like, and E designates means of connection between the container A and such structure D. Specifically this may be a rope or strap 8, and in Fig. 7 such means of connection E and means D are illustrated as comprising an auxiliary parachute device 9 which, when cast into space with the packed parachute and the user, extends operatively and acts as a support, analogous to the members D and 8, so that the sequence of operations to free the parachute device within the container A may be performed.

I will now describe one specific form of construction, formation, inter-relation and combination of parts and features embodying my invention, and state the operation of the same. It is, however, to be understood that I do not thereby desire to limit the invention, directly or impliedly, in its construction, to any such specific embodiment.

The means of connection C are shown as comprising a vest 10 which is applied to the body of the user, and may have suitable straps, bands, cords or the like 11 to be passed about and over or under the body or body and limbs of the user, so as to constitute an effective and comfortable and positive means of suspension connecting the user with the parachute device in use. This vest or the like 10 may have a rearward pocket 12 accommodating and normally supporting the container A and the parachute device B therein, when such parts are worn as a pack. The container A comprises a preferably textile body 13 of the proper depth and other dimensions to receive and hold the parachute device, being in effect a bag or envelop and being closed upon all sides and ends with the exception of that through which the parachute device is introduced or withdrawn, at which side, which will constitute the front when the device is worn as a pack upon the back of the user, are provided two flaps 13^a and 13^b which are brought nearly together and so held, when the parachute device is within the container, by a frangible fastening, a cord or the like, 14. In the middle portion of the container are provided two further flaps, 13^c and 13^d,

preferably spanning the interior of the container at right angles to the flaps 13^a and 13^b, springing from the other two sides of the container walls 13, but lying substantially parallel with such other flaps. These flaps 13^c and 13^d are brought nearly together and normally so held by a frangible connection such as a cord or the like 15. Together, these two sets of flaps hold the parachute device within the container, such action being supplemented by a further similar frangible device or cord 16 by which the apex of the parachute body is attached to the container wall 13, directly beneath the means of connection E, or at a point most remote from the flaps 13^a and 13^b. In introducing the parachute device within the container, the parachute body or envelop 17 is first placed within the container, in folded condition, or in superposed folds. The flaps 13^c and 13^d, and the flaps 13^a and 13^b are separated, respectively, and held at the sides of the container during the operation of packing the parachute device within the latter. When the suitably arranged folds of the parachute body 17 are properly disposed within the container, the load suspending cords 18 are lead to the center of the container and down or out through the space which is provided upon bringing the flaps 13^c and 13^d together and connecting them by the cord 15. The said cords 18 are then carefully disposed within the container over the flaps 13^c and 13^d, in superposed coils, and the several coils or turns of the grouped cords are separated from each other to a greater or less degree by suitable loose separators 19, such as newspaper sheets or a plurality of the same, sheets of card-board, or other material light in weight. When the grouped cords 18 have thus been coiled and spaced as to the several coils within the container, the weight or load supporting ring 20 of the parachute device is disposed within the container and upon or beneath or against the coiled grouped cords 18, and a flexible connector or member c of the means of connection C is in part disposed within or beneath the flaps 13^a and 13^b which are now brought together over the housed parachute device, such flexible member c, consisting of a pair of straps or the like, being extended through the narrow space between adjacent edges of the flaps 13^a and 13^b which are held in such relation by the frangible cord 14; and such straps or the like c are connected each at one end with the ring 20 and at the other end with the vest or the like 10 of the means of connection or suspension C. The said vest 10 may then be brought up against the container A with its inclosed parachute device, where it is held detachably by flaps 21 which are connected with the vest by snap fasteners 22 or the like which permit the release of the vest 10 from the container when a certain degree

of quick pull or jerk is imparted to the vest, as in the drop of the wearer of the same. The frangible cords 14, 15 and 16 and the snap fasteners 22, which latter may of course be supplanted by similar frangible cords, all constitute means yieldingly performing their several holding functions, which functions are interrupted when sufficient strain is brought to bear upon such parts.

In using the packed parachute embodying the invention, when the device is worn as a pack by means of the vest or the like 10, the wearer upon leaping or being cast into space executes a slight drop with the packed 10 parachute, until the strap or rope 8 is tautened, or the container 13 may be directly and immediately connected with the structural member D or the like, and the detachable or yielding connections at 22 between 15 the vest and container may be dispensed with, permitting the user to move about upon the flying machine or the like, within the limits permitted by the length of the straps c. When the yielding or temporary 20 connections 22 are employed, as soon as the weight of the wearer is imposed upon the device, the rope 8 is tautened the snap fasteners or the like 22 will yield, permitting 25 the vest and the wearer to drop from the supported container and parachute device 30 therein until the parts assume the positions shown in Fig. 3. Where no fastening is provided, as at 22, between the vest and the container, the first stage of drop or descent 35 will be the second stage just described, namely that which results in an extension of the straps c, omitting the first stage, which, as described, involving the tautening of the rope 8. When the straps c are tautened by 40 the pull of the weight of the user, the cord 14 will break, the flaps 13^a and 13^b will fall or open, the supporting ring 20 will drop, and the grouped cords 18 will commence to 45 uncoil, without fouling, due to the inter- position of the spacers 19 between the several 50 coils, which spacers are scattered in open space. This action takes place during the third stage of drop illustrated in Fig. 4. The tautened cords 18 now strain upon the holding cord 15 uniting the flaps 13^c and 13^d, 55 breaking such cord, and the fourth stage of drop commences, which is accompanied by an unfolding of the folds of the parachute body or envelop 17, the flaps 13^c and 13^d having opened and fallen. These folds open 60 out or straighten out without fouling, such stage of drop being illustrated in Fig. 5. When this stage of drop has been completed, strain is brought to bear upon the frangible 65 cord 16 which breaks, and the entire para- chute device comprising the ring 20, cords 18 and body or envelop 17, with the spacers 19, are now entirely freed from, and the last part thereof, namely the apex of the para- chute body, descends from the supported

container 13, as shown in Fig. 6. In the sixth stage of drop, which is not illustrated, the parachute body opens out into operative form, in the usual manner, and the parachute and wearer descend gradually and 70 safely.

In the modified form of construction, illustrated in Fig. 7, the parachute body or device 9 simply takes the place, as stated, of the supporting structure D and rope 8, suspending the container A during the several successive stages of drop or descent above enumerated and explained, and during which the same operations of releasing the 75 parachute device B for use are performed. 80

It will be noted that the operation of the device is entirely automatic, and by well defined sequences of operation and release the several parts and features are prevented from fouling or becoming entangled, the 85 producing of which result is assisted by the spacers 19 and by the yieldingly connected flaps of the pairs 13^a and 13^b and 13^c and 13^d. The aeronaut or other user may safely cast himself or be cast into space, either for spectacular purposes or as a life-saving act, such as for instance upon lost control of a flying machine, or breakage thereof or explosion of the prime mover thereof. 90

The packed parachute is relatively small 95 in compass and light in weight, and when worn upon the person does not interfere with comfort or free and easy movement of the limbs and muscles; and, as stated, it may be remotely attached to the flying machine 100 or other structure, and connected with the user by the straps c and the vest or the like 10. thus ridding the user of the impost of the parachute device and container. The vest 10, may of course, constitute an article 105 of regular wearing apparel of the aviator or other user.

Having thus described my invention, I claim and desire to secure by Letters Patent:

1. A packed parachute comprising a container, a parachute body folded within the container and yieldingly connected therewith, means for yieldingly holding the folded 110 parachute body within the container, load supporting cords connected with the parachute body and coiled within the container, means for yieldingly holding said cords so coiled within the container, and means for connecting said load-supporting 115 coils to a load. 120

2. A packed parachute, comprising a container, a parachute body folded within the container and yieldingly connected therewith, means for yieldingly holding the folded 125 parachute body within the container, load-supporting cords connected with the parachute body and coiled within the container, means for yieldingly holding said cords so coiled within the container, and means for connecting said load-supporting 130

coils to a load; there being spacer devices interposed between the said coils of the load-supporting cords.

3. A packed parachute, comprising a container, a parachute body folded within the container and yieldingly connected therewith, means for yieldingly holding the folded parachute body within the container, load-supporting cords connected with the 10 parachute body and coiled within the container, means for yieldingly holding said cords so coiled within the container, and means for connecting said load-supporting cords to a load; there being spacer devices 15 interposed between the said coils of the load-supporting cords; and means being provided for supporting the container.
4. A packed parachute, comprising a container, a parachute body folded within the 20 container and yieldingly connected thereto, means for yieldingly holding the folded parachute body within the container, load-supporting cords connected with the parachute body and coiled within the container, 25 means for yieldingly holding said cords so coiled within the container, a flexible connection for said container, and means for

connecting said load-supporting cords to a load; there being spacer devices interposed between said coils of the load-supporting 30 cords.

5. A packed parachute, comprising a container, a parachute body folded within the container and yieldingly connected thereto, means for yieldingly holding the folded 35 parachute body within the container, load-supporting cords connected with the parachute body and coiled within the container, means for yieldingly holding said cords so coiled within the container, a flexible connection 40 for said container, and means for connecting said load-supporting cords to a load; there being spacer devices interposed between said coils of the load-supporting cords; said container being suspended from 45 a flying machine or the like by said flexible connection.

In testimony whereof, I have signed my name to this specification in the presence of two subscribing witnesses.

GLENN L. MARTIN.
